UNITED STATES PATENT OFFICE.

CHARLES BRAYTON BIRD, OF SIOUX CITY, IOWA, ASSIGNOR TO ELLEN O. BIRD, OF SAME PLACE.

SUSPENDER-BUCKLE.

SPECIFICATION forming part of Letters Patent No. 340,088, dated April 20, 1886.

Application filed January 28, 1885, Serial No. 154,215. Divided and this application filed August 24, 1885. Serial No. 175,144. (No model.)

To all whom it may concern:

Be it known that I, CHARLES BRAYTON BIRD, a citizen of the United States, residing at Sioux City, in the county of Woodbury, 5 State of Iowa, have invented certain new and useful Improvements in Buckles; and I hereby declare the following to be a full, clear, and exact description of the same.

My invention relates, generally, to a buckle 10 by means of which one strap is adjustably connected to another, and more particularly to a buckle in which the strap is connected and adjusted by means of a slide provided with a swinging bearing-tongue. Such a device as 15 the latter is applicable to and is generally used upon suspenders, and for the sake of convenience in the description and drawings I have represented my invention as thus applied.

My invention consists in a buckle comprising 20 a slide of sufficient dimensions to receive the web of the suspender or other strap, provided on one side with an opening for the bearing-tongue, and having guides formed on opposite sides of such opening to receive corresponding guides upon a slide or guard, which 25 is provided for the purpose of covering the bearing-tongue, and has means formed upon it for the attachment of the buckle to the opposing strap or reach or other object to which 30 the strap is to be adjustably connected.

My invention further consists in the particular details of construction which I prefer to employ in carrying out my invention.

In the drawings, Figure 1 is a front elevation 35 of my device adapted to the connection of the strap and ends of a suspender; Fig. 2, a transverse section of the same on the line 22, Fig. 1; Fig. 3, a longitudinal section of the same on the line 33, Fig. 2; Fig. 4, a modified construction.

A is the strap, and B the reach or ends, of a suspender.

C is the slide, to receive the web or strap of the suspender, which I preferably make in the 45 manner shown the drawings—that is to say, of a single blank of metal having its sides turned over to leave a rectangular passage for the strap. In forming this slide I prefer to use a blank of such a size only that when turned 50 over its edges will not meet, but will leave an opening, t, to receive the bearing-tongue D,

which will be hereinafter described, and I prefer, also, to turn back the edges, as shown, to provide on opposite sides of the opening t the guides s. I prefer also to cut the blank in 55 such a way that the two opposite sides converge, so that when the edges are turned over to form the slide they will leave an opening, t, with converging sides, the guides s formed upon them converging also. Such an ar- 60 rangement, the advantage of which will presently appear, is illustrated in Fig. 1.

Toward the upper end of the guides s, I provide bearings in the form of apertures, as shown, which support the bearing-tongue D. 65 This bearing-tongue comprises the leaf r and bearing-part p, the latter being preferably serrated at its bearing edge. A convenient way to form this feature is to make the parts r and p of a single piece, bent twice, as shown 70 in cross-section in Fig. 3, leaving a passage to receive the bearing-pin or pivot o, which enters the apertures formed in the guides s.

The guides may be provided with projections instead of holes, and the pivot-pin o may 75 be omitted, the projections entering the passage formed in bending the bearing-tongue in the well-known manner. A plate, E, which constitutes the cover or guard, is provided with guides s' upon its edges, preferably by having 80 them turned over, as shown, to engage and slide upon the guides s formed upon the slide C. Where the guides s are made to converge, I prefer to form the guard E of the same configuration. I provide the guard E with means 85 to permit its connection with the suspender-end or other objects to which the strap is to be connected, which may consist in the three slots n shown in Fig. 1, the hook shown in Fig. 4, or any other construction suitable to 90 the particular purpose to which the buckle is to be applied.

The operation of the device is as follows: The guard E being removed, the tongue r of the bearing-tongue D raised, raising with it 95 the bearing part p, and leaving a free passage through the slide for the web or strap, which is then inserted to the proper point of adjustment. The tongue r is thereupon pressed downward, causing the bearing part p firmly 100 to engage and retain the strap at the point of adjustment. The guard E is slid upon the

guides s , and covering the tongue D prevents its release from its engagement with the strap. Where the buckle is used upon suspenders, I prefer to make the guard large enough entirely 5 to cover the tongue, which is thus prevented from coming in contact with the clothing; but this construction is not in all cases essential. The draft upon the guard, to which is attached the reach or other device, is in the direction 10 of the diverging guides s and s' , so that the use of the device serves to maintain the guard and hence the bearing-tongue in its position, and entirely prevents the displacement of the strap.

15 I have shown in Fig. 4 a modified construction, which, while not presenting the advantages found in the construction in Fig. 1, is still effective to accomplish the purpose of my invention. Instead of forming diverging 20 guides s and s' , they are made parallel, and I provide at the lower end of each a shoulder or stop, m , which impinges against the stop on the other. It is obvious that the stops m may be formed at the upper end of the guides s and 25 s' , if desired, and accomplish the same purpose. It is quite clear that the slot t need be of a length sufficient only to receive and permit the rotation of the bearing part p of the bearing-tongue, though, owing to convenience of 30 manufacturing the device with a continuous opening, I prefer such a construction; but I do not limit myself to any particular arrangement in this regard. It is of course not essential that the sides of the opening t or the guard 35 E shall be parallel with the guides; nor that the guides s and s' shall be formed in the particular manner shown. They may be separately formed upon the parts and any ornamental design or configuration desired given 40 to the slide and guard.

A device constructed in accordance with my invention presents many advantages in its neatness, durability, and security. The accidental raising or lowering of the bearing-tongue is 45 prevented, as well as the bending of the tongue from accidental causes. It avoids the wearing or tearing of clothes when used as a suspender-buckle, inasmuch as it at all times presents a smooth surface. Besides being capable of 50 ornamentation, it presents a neat and attractive device.

The present application is a division of an application for an improvement in suspenders filed by me January 28, 1885, Serial No. 154,215.

What I claim as new, and desire to secure 55 by Letters Patent, is—

1. A buckle comprising a slide carrying a pivoted angular clamp and having guides formed upon it at opposite ends of the clamp, and a guard or cover moving upon the guides 60 and entirely covering the clamp and preventing its release, substantially as described.

2. A buckle comprising a slide, C , carrying a pivoted bearing-tongue, D , and having guides s formed on the slide on opposite sides of the 65 bearing-tongue, and a guard having guides s' , substantially as described.

3. A suspender-buckle comprising a slide provided with an opening to receive the bearing-tongue, an angular bearing-tongue pivoted 70 in the said opening, oppositely-converging guides formed on the slide on each side of the opening, and a guard or cover provided with guides to engage with and move upon the guides upon the slide and having means of 75 connection to the suspender-end, substantially as described.

4. A buckle comprising a slide formed of a single piece of metal bent to leave a passage 80 for the strap and leave a space between the opposite edges to receive the bearing-tongue, and having its opposite edges turned back to form guides, an angular bearing-tongue pivoted in the guides thus formed, and a guard covering the tongue and preventing its release, formed of a single piece of metal having 85 its edges turned over to form guides to slide upon the guides on the slide and provided with slots n , substantially as described.

5. A buckle comprising the following elements: a slide, C , having opening t , having converging sides and guides s , a bearing-tongue, D , pivoted in the opening t , and a guard, E , having guides s' , substantially as 90 described.

CHARLES BRAYTON BIRD.
